George C. Heinrichs

UNITED STATES PATENT OFFICE.

FRANK WASCHEK, OF HAMTRAMCK, MICHIGAN.

PARACHUTE.

Application filed March 5, 1921. Serial No. 450,021.

To all whom it may concern:

Be it known that I, FRANK WASCHEK, a citizen of Poland, residing at Hamtramck, county of Wayne, and State of Michigan, 5 have invented certain new and useful Improvements in Parachutes, of which the following is a specification.

This invention relates to improvements in parachutes, particularly parachutes to be 10 used by persons trying to escape from a burning building.

It is the principal object of the invention to provide a parachute of this character which can be conveniently stored when not 15 in use, quickly made ready for use and which is provided with a seat and holder for persons making a descent from a burning skyscraper or other tall building.

Another object of the invention is the provision of a parachute which is extremely simple and inexpensive, but which however, is of positively serviceable construction.

In the accompanying drawing, I have disclosed certain embodiments of the invention 25 and have described them in detail herein-after, but as the invention is susceptible of various modifications, the forms hereinafter set forth, and which are shown in the drawing, are to be considered as illustrative, 30 rather than restrictive, of the scope of the invention.

Furthermore it will be observed that all the features described and illustrated co-operative to form one single device intended 35 for the positive and effective saving of a person or persons endangered by fire.

In the accompanying drawing:

Figure 1 is a side view partly in section of a parachute constructed according to 40 the present invention, in its open position.

Figure 2 is a top plan view of a seat combined with the parachute.

Figure 3 is a detail view of a belt to be used in connection with the parachute.

Figure 4 is a detail view of a basket or hamper to be used with my parachute for saving the lives of one or more children, and

Figure 5 shows in side elevation a movable platform adapted to be quickly secured 50 to a window sill, from which the descent by parachute may be inaugurated.

The parachute comprises a rod 10 provided with a collar 11 near its upper pointed end to which is secured a guide 12 for the

roof 13 which is made of strong canvas or 55 like suitable material, and provided with strengthening elements 14 on its upper side to which eyes 15 are secured in which the ends of cables 16 are anchored, the inner ends of said cables being guided over rollers 60 17 suitably held in a sleeve 18 slidably up and down along the rod 10.

A similar stationary sleeve 19 is secured near the upper end of the rod under the guide 12 and carries rollers 20 over which 65 cables 21 are guided and then fastened to eyes 22 secured to the element 14.

At the upper end of the movable sleeve 18 resilient hooks 22' are provided having upper angularly disposed handles 23 and hook 70 elements 24 intermediate their ends engage suitable notches or grip over shoulders provided in a stationary sleeve 25 on the rod 10 between the stationary sleeve 19 and the movable sleeve 18.

At the lower end of the sleeve 18, a hook 26 and a ring 27 are arranged for a purpose which will be hereafter more fully explained.

At the lower end of the rod 10 a seat 28 80 is located and in front of the same two rest bars 29 forming rests for the legs of a person occupying the seat.

Above the seat 28 a catch 30 is provided on the rod 10, adapted to be engaged by the 85 hook 26.

As illustrated in Figure 3 a belt 31 may be used in connection with the parachute in order to secure a person who is liable to become dizzy, to the parachute before descending, to prevent the person from falling off the same, and for this purpose the belt has a cable 32 attached thereto provided with a hook 33 at its end which can be hooked into the ring 27.

In Figure 4 a hamper 34 is illustrated provided with straps 35 to be guided over the shoulders of a person in the ordinary well known manner and to be fastened with their hooks 36 in eyes or rings 37 at the lower 100 edge of the hamper.

The cover 38 of the hamper or basket is provided with a means 39 for securing it to the hamper, said cover having air holes 40 and adapted to be closed over the hamper by 105 a snaplock 41 or the like.

In Figure 5 a platform 42 is shown which may be hooked over a window sill by means

of its hook 43 provided with teeth 44 while the platform is hung outside of a window, the floor 45 being braced against the vertical member of the hook part 43 by means 5 of the bars 46, 47 and 48 as illustrated.

The device operates as follows: If a fire breaks out, the platform 42 is placed with its hook 43 against the outer wall of a house so that the teeth 44 enter the woodwork of 10 the inner window sill, the person carrying the hamper 34, into which one or more children to be saved have been placed, steps onto the platform 45 and opens the parachute, by securing the hooks 24 in the sleeve 25 and 15 takes his seat on the seat board 28 with his legs supported by the bars 29 and then jumps off the platform, after first having secured the hook 33 of the cable 32 attached

to the belt 31 in the ring 27, when the person fears getting dizzy during the descent. 20

Having thus described my invention, what I claim, is:—

In combination with a parachute of the character described, having a rod, a sleeve adapted to be displaced along said rod in 25 longitudinal direction, a seat at the lower end of said rod, rest bars in front of said seat a ring on said sleeve adapted to be engaged by a hook of a belt secured to the 30 waist of a person on said seat for preventing the person from falling off during the descent of the parachute.

In testimony whereof I have affixed my signature.

FRANK WASCHEK.
